UNITED STATES PATENT OFFICE.

WILLIAM E. JORY, OF SAN FRANCISCO, CALIFORNIA.

WAVE-POWER.

SPECIFICATION forming part of Letters Patent No. 281,370, dated July 17, 1883.

Application filed March 13, 1883. (No model.)

To all whom it may concern:

Be it known that I, WILLIAM E. JORY, of the city and county of San Francisco, State of California, have invented an Improved Wave-5 Power; and I hereby declare the following to be a full, clear, and exact description thereof.

My invention relates to that class of devices specially adapted to be affected by the waves, and commonly known as "wave-powers."

10 It consists in a float having vertical screws connected with the main shaft by gearing, which transmits the vertical movement of said screws in the manner I shall hereinafter particularly describe.

15 The object of my invention is to provide a simple and effective means for utilizing the power of the waves or tides.

Referring to the accompanying drawings, Figure 1 is a side elevation of my device. Fig. 20 2 is a plan of the ratchets H, gear I, and pawl i. Fig. 3 is a detail section of same on screw.

25 A is a wharf or other suitable foundation secured in the water. Under it, and between it and the supports or piles, is a large float, B, upon the water.

C C are the standards, one at each end and one in the middle, connected loosely with the float by a ball-and-socket joint, designated by c, whereby the float may adapt itself to the 30 changing surface of the water without affecting the perpendicularity of the standards. These standards extend up through the wharf loosely, and have vertical screws D secured to their tops.

35 E E are side supports or frame-work, having projecting arms a a, between and in the ends of which is mounted the driving-shaft F.

Arms e extend inwardly and serve as guides for the vertical end screws, D, and a bracket, 40 G, secured to the wharf, serves as a guide for the central screw.

Mounted upon the screws D are ratchets H. These are loose upon the screws, and have studs h, traveling in the threads of the screw, 45 whereby the vertical movement of the screws will turn the ratchets, Fig. 3.

Mounted loosely upon the screws are gears I, having pawls i, held to place by springs i'. These pawls are adapted to be engaged by the 50 ratchets when turning in one direction, but

not in the other, as I shall explain. The end gears, I, mesh with pinions J on the driving-shaft. The central gear meshes with a pinion, K, on a supplementary shaft, L, the top of which is provided with a gear, M, meshing 55 with a pinion, J', on the driving-shaft. The threads of the end screws have an opposite direction, one being right hand and the other left hand, in order to drive the shaft in the same direction. The center one has its threads 60 corresponding to one of the ends for a similar purpose. The pawls i of the end gears, I, are so arranged that when the screws move up, their ratchets H will engage them, and so turn the gears; but when the screws move down, 65 the ratchets do not engage the pawls, and no movement results. The pawl of the center gear is arranged in an opposite manner, so that it is engaged by the ratchet only when the central screw moves down.

70 The operation of the device is as follows: A wave striking under one end of the float elevates that end and depresses the other. One end screw is elevated and transmits motion to the driving-shaft, while the other is lowered and does not operate, and vice versa. The float, by being connected with ball-and-socket joint, may thus move freely. All downward movement of the float is transmitted 75 through the central screw. The screws are made long enough to allow for the rise and fall of the tide and still operate. Any movement of the float is thus transmitted to the driving-shaft.

Having thus described my invention, what 80 I claim as new, and desire to secure by Letters Patent, is—

1. In a wave-power, the float B, the standards C, connected loosely therewith, and the vertical screws D, on the standards, in combination with the ratchets H, loosely mounted on the screws, and having studs h, traveling in their threads, the driving-shaft F, and intermediate gears for transmitting the motion of the ratchets to the shaft, substantially as 90 herein described.

2. In a wave-power, the float B, the standards C, connected loosely therewith, and the vertical screws D on the standards, in combination with the loose ratchets H, on said screws, 95 100

having studs *h*, traveling in their threads, the gears *I*, loose on said screws, and having pawls *i*, engaged by the ratchets, and the driving-shaft *F*, having gears engaging with gears *I*, substantially as herein described.

3. The float *B*, having loose end standards, *C*, and end screws, *D*, having threads of different direction, in combination with the ratchets *H*, having studs *h*, traveling in their threads, the loose gears *I*, having pawls *i*, engaged by the ratchets when the screws move up and disengaged when they fall, the driving-shaft *F*, and pinions *J*, meshing with gears *I*, whereby the action of the waves on either end of the float may be transmitted to the driving-shaft, substantially as herein described.

4. The float *B*, having a central standard,

C, loosely connected therewith, and the central vertical screw, *D*, on said standard, in combination with the ratchet *H*, having a stud, *h*, traveling in the thread of the screw, the gear *I*, having a pawl, *i*, adapted to be engaged by the ratchet when the screw moves down and to disengage when it moves up, the supplementary shaft *L*, having pinion *K*, and gear *M*, and the driving-shaft *F*, having pinion *J'*, all arranged and operating substantially as herein described.

In witness whereof I hereunto set my hand.

WILLIAM E. JORY.
